UNITED STATES PATENT OFFICE.

FRANK DEWHURST, OF PETERBOROUGH, ENGLAND, ASSIGNOR TO BAKER PERKINS LIMITED, OF PETERBOROUGH, ENGLAND.

APPARATUS FOR THE DRYING AND PRESSING OR SHAPING OF GARMENTS AND THE LIKE.

Application filed April 30, 1927, Serial No. 187,917, and in Great Britain May 5, 1926.

This invention relates to apparatus, for use in laundries and for like services, whereby the drying and pressing or shaping of garments and the like are effected by means 5 such that the said operations are effected by the temporary confinement or trapping of heated air within the garment for extending the latter and so shaping the same, simultaneously with the drying, as to dispense 10 with subsequent ironing or calendering.

The object of this invention is to provide improved apparatus for facilitating such treatment of the garments, and it comprises the combination with a hot air duct or ducts 15 of means for carrying the garments along the duct and in such communication with its interior as will keep them charged with or extended by the hot air throughout such conveyance.

20 The invention further comprises the provision of the supplementary means for the treatment of the garments in the manner hereinafter described.

25 Referring to the three accompanying sheets of explanatory drawings:—

Figure 1 is a side elevation, Figure 2 a plan and Figure 3 an end view of one form of apparatus in accordance with this invention and constituting what may be termed 30 an air ironer.

Figure 4 is an elevation showing (to a larger scale) a portion of one of the air ducts or trunks, and Figure 5 a sectional end view of the same.

35 Figure 6 is a sectional end view showing a detail hereinafter referred to.

The same reference letters in the different views indicate the same or similar parts.

In the apparatus in accordance with this 40 invention as illustrated by the drawings, I preferably employ a pair of ducts or trunks *a* disposed in parallel and with sufficient space between them to accommodate a supplementary conveyor for the purpose herein- 45 after described. In association with each of the said ducts there is arranged an endless belt conveyor *b*, one run or reach of which (preferably the upper) is on the exterior of the duct whilst the other reach (preferably 50 the lower) passes through the duct.

A gap or aperture *c* extends along the underside of each duct and beneath the same a supporting guide or runway *d* is provided

for a number of nozzle like slides or sliding nozzles *e*, each of which serves to support a 55 garment (as, for example, an overall or combination garment) and to admit the hot air thereto from the duct. One of said overalls or the like is indicated by dotted lines at Figure 1. Such slides or nozzles *e* with the garments suspended therefrom are placed on the said runway (at the loading end *A* of the apparatus) and conveyed or pushed therealong by means of carriers or abutment pieces *f* attached to the endless 60 belt *b*. Adjacent each of the said carrier or abutment pieces *f* an aperture *g* (Figure 2) is formed in the belt or conveyor *b* to register with a sliding nozzle *e*, so that whilst the latter is carried along by the belt the 70 hot air from the duct *a* has access to the garment and keeps the same extended or pressed out whilst it is drying.

Each belt or conveyor *b* is mounted on or passes around the end wheels or pulleys *h*. 75 The two pulleys at one end of the apparatus are affixed to the one shaft *i* which is driven through chain wheel *j* from the worm or gear box *k* forming part of or arranged in association with the electric or other driving motor *l*.

80 The air required is drawn by a fan *m*, driven by an electric motor *n* or otherwise, through a heating chamber *o* and delivered into the ducts *a* aforesaid under a sufficient 85 pressure to give the required extension or inflation of the garments. The said chamber *o* is fitted with steam pipes or other ordinary means for heating the air in its passage through the chamber under the action 90 of the fan *m*.

95 Between the ducts *a* aforesaid there is disposed, in the example illustrated, an endless chain conveyor *p* with hooks or suspension members *q* by which the garments may be suspended, after detachment from the sliding nozzle *e* at the unloading end *B* (Figures 1 and 2) of the apparatus, and so moved along with said conveyor for subjection to an additional drying action. In this manner the wrist bands or other thickened parts of a garment may be subjected to a supplementary drying action when the same is necessary or desirable. The upper end of each hook or suspension member *q* of the 100 chain conveyor *p* is provided, as is shown

more clearly at Figure 6, with rollers *r* which are supported by the fixed track *s*. The hooks or suspension members *q* are attached to the chain conveyor *p* and thus in 5 addition to sustaining the suspended garments they serve also to support the conveyor itself as it travels between and around the end wheels or pulleys *t*. The conveyor *p* is driven from the shaft *i* (Figures 1 and 10 2) aforesaid by means of chain gear *u* and bevel wheels *v*, one of the latter being mounted coaxially with one of the end wheels or pulleys *t* of the conveyor *p*.

The casing *w* of the apparatus, between 15 the loading end *A* and the unloading end *B* is made to form a pair of outer chambers as *x* extending beneath the air ducts *a*, and a central chamber *y*. The sides of the said chambers may be hinged and fitted on the 20 interior with hooks or the like for the reception in a stretched or extended form of curtains and other fabrics to be dried to a finished shape and condition. The said curtain drying and like operations may be 25 effected without interference with the drying of garments by passing same along the air ducts in the manner aforesaid.

The conveyors as *z* on the outer sides of 30 the apparatus serve for the return of the goods, or the sliding nozzles *e*, from the exit *B* to the entrance *A* of the apparatus. The said conveyors *z*, in the example illustrated, are driven through chain gears 1 and 2 from the wheels or pulleys *h* of the air duct con- 35 veyor *b* at the entrance or loading end of the apparatus.

In the use of the machine or apparatus, an operative or operatives at the loading end 40 *A* inserts a nozzle *e* in the neck of each garment, as for example the garment 3 indicated by dotted lines at Figure 1, and ties or fastens the sleeve and feet ends so that the garment forms as it were a closed bag. The nozzle (with the garment hanging 45 therefrom) is then placed on the track *d* beneath one or the other of the air ducts *a*. As it is thus supported in alignment with the aforesaid carrier or abutment pieces *f* one of the latter, by the movement of conveyor *b*, will push the nozzle along the track *d* and so carry the garment to the exit or unloading end *B* of the machine. Throughout 50 its movement the garment will be kept charged with and extended by the hot air admitted from air duct *a* through one of the conveyor apertures *g* aforesaid. When the garment emerges at the exit *B* an operative withdraws it from the track *d*, releases the nozzle and places same on one of the conveyors *z* for return to the loading end *A*, and, after removing the ties or fastenings 60 from the sleeve and feet ends of the garment, hangs the latter from one of the hooks of the central conveyor *p* by which it is carried 65 to the inner end of the central or final air-

ing chamber *y* and thence back again to the exit *B* for removal from the machine in an effectually dried condition.

Though the apparatus or machine as illustrated is provided with two air ducts *a*, each having a conveyor *b* and other parts associated therewith as aforesaid, and with a central conveyor *p* between said ducts, the invention is not limited to such an arrangement. 75

Having thus described my invention what I claim as new and desire to secure by Letters Patent is:—

1. In apparatus for the drying and pressing or shaping of garments and the like, the combination comprising an air duct, means for carrying the garments along the exterior of said duct, and means whereby the air from said duct obtains access to and extends the garments as they progress along 80 the duct.

2. In apparatus for the drying and pressing or shaping of garments and the like, the combination comprising an air duct, a runway beneath said duct, nozzles mounted on 85 said runway and supporting said garments and admitting air thereto from said duct, and a conveyor whereby said nozzles and garments are moved along said runway.

3. In apparatus for the drying and pressing or shaping of garments and the like, the combination comprising an air duct, a runway beneath said duct, nozzles mounted on 90 said runway and supporting said garments, an endless conveyor, and abutment pieces 100 transmitting the movement of the conveyor to said nozzles and the garments they support.

4. In apparatus for the drying and pressing or shaping of garments and the like, the combination comprising an air duct having 105 a gap extending along its underside, a runway beneath and adjacent to the said gap, nozzles mounted on said runway and supporting said garments, an endless conveyor 110 having one run or reach on the exterior and the other run or reach on the interior of the duct and forming a cover for said gap, abutment pieces transmitting the movement of the conveyor to said nozzles and the garments they support, and apertures in the conveyor adjacent said abutment pieces for the passage of the air from the duct through 115 the said nozzles to the interior of the garments.

5. In apparatus for the drying and pressing or shaping of garments and the like, the combination comprising an air duct, means for carrying the garments along the exterior of said duct, means whereby the air from said duct obtains access to and extends the garments as they progress along the duct, and a conveyor for the return of the garments from the exit to the entrance of the 125 duct.

6. In apparatus for the drying and pressing or shaping of garments and the like, the combination comprising an air duct, means for carrying the garments along the exterior of said duct, means whereby the air from the duct obtains access to and extends the garments as they progress along the duct, and means for subjecting the garments to a supplementary drying after the movement 10 of the same along the duct.

7. In apparatus for the drying and pressing or shaping of garments and the like, the combination comprising an air duct, means for carrying the garments along the exterior of said duct, means whereby the air from the duct obtains access to and extends the garments as they progress along the 15

duct, and means for maintaining the duct charged with hot air.

8. In apparatus for the drying and pressing or shaping of garments and the like, the combination comprising a central and two outer chambers, an air duct in each of said outer chambers and means for carrying the garments along the said duct and for admitting to them the air from the duct as they progress along the same, and a conveyor whereby the garments are carried through the said central chamber after passing along the outer chambers.

In testimony whereof I have signed my name to this specification.

FRANK DEWHURST.
